DRILL BIT

Filed April 8, 1946

PATRICK ADAMSON

32 The Firm of Charles M. Hall

Attys.

WITNESSETH that I, PATRICK ADAMSON, a citizen of Canada, residing at Haileybury, Ontario, Canada, have invented a new and useful improvement in Drill Bits, as hereinafter set forth:

My invention relates to a drill bit assembly having a plurality of substantially cylindrical, diamond or other abrasive impregnated or surfaced, bits, each positively driven and arranged substantially equidistant from the axis of the assembly, with one of the bits of sufficiently larger diameter to overlie the geometrical center of the hole to be drilled, whereby there is positive grinding action at that point due to the relatively high linear speed of the abrasive particles in passing therover.

It has heretofore been the practice in oil drilling to use hard bits having a chipping or cutting action.

Due to the fact that such bits are strong and can stand percussive forces, any cone of rock left uncut at the geometrical center of the hole being drilled will be crushed or broken free by the action of the drill bit. The crushed or broken portions of the rock are then forced out of the way by the circulating fluid.

In accordance with my present invention, however, rotary cutters which may be impregnated or surface-set with abrasive particles, such as diamonds, are used in place of the previous hard alloy cutter.

With the use of such abrasive bits, a grinding action, rather than a cutting action, is produced. There is no percussive force possible in the case of diamond drill bits, nor is there

sufficient clearance provided for cuttings to pass away from the face of the bit of greater size than

are normally formed by the action of the diamonds in breaking down the granular structure of the rock.

Consequently, in the use of diamond bits, I have found it necessary to provide for a positive grinding action over the entire surface of the hole to be drilled, including the geometrical center of the hole. I accomplish this by providing a plurality of substantially cylindrical bits having lateral and lower grinding surfaces, with one of the bits of larger diameter than the others and with the bits so arranged that the peripheral marginal portion of the larger size bit overlies the geometrical center of the hole to be drilled. The bits are positively driven, independently of the rotation of the drill bit assembly as a whole, with the result that the linear speed of the peripheral marginal grinding portion of the larger size bit over the center of the hole gives an efficient grinding action at that point. The blind center that would otherwise exist in the case of previously used drill bits is thereby eliminated. By virtue of this arrangement, diamond bits of my invention may be used for drilling purposes where heretofore abrasive type bits have not proved satisfactory.

It is therefore an important object of this invention to provide a drill bit assembly having positively driven rotary bits provided with diamond or other abrasive particles, impregnated throughout or set upon the surfaces of the bits,

and arranged to provide a grinding action over the entire surface of the hole to be drilled, including the geometrical center of the hole, and to thereby eliminate the blind center that would otherwise exist in the case of previously used abrasive type bits.

It is another important object of this invention to provide a drill bit assembly in which the rotary cutters are so arranged as to eliminate the so-called "blind center" in the drilling operation.

It is a further important object of this invention to provide a drill bit assembly in which

the rotary cutters are so arranged as to eliminate the so-called "blind center" in the drilling operation.

It is a further important object of this invention to provide a drill bit assembly having a

plurality of substantially cylindrical, diamond or other abrasive impregnated or surfaced, bits, each positively driven and arranged substantially equidistant from the axis of the assembly, with one of the bits of sufficiently larger diameter to overlie the geometrical center of the hole to be drilled, whereby there is positive grinding action at that point due to the relatively high linear speed of the abrasive particles in passing therover.

Other and further important objects of this

invention will be apparent from the disclosures in the specification and the accompanying drawings.

Figure 1 is a bottom plan view of a drill bit assembly embodying the principles of my invention;

Figure 2 is a sectional view, with parts in elevation, taken substantially along the broken line

II-II of Figure 1; and

Figure 3 is a sectional view taken substantially along the line III-III of Figure 2.

The reference numeral 10 indicates generally a drill assembly embodying the principles of my invention. Said drill assembly comprises a bit blank 11 having an upper externally threaded

conical portion 12 for threading into a correspondingly internally threaded socket 13 of a holder 14, the latter being generally called a "sub."

The holder, or "sub," 14, is, in turn, threaded into the heavy drill collars attached to

the lower end of the string of drill pipes used in the drilling of oil wells and the like.

As shown, the drill assembly 10 is intended to be attached to the shaft 15 of a turbo-drill. Said shaft 15 extends freely through the holder 14

and the bit blank 11. The lower end of said shaft

15 carries a pinion 16 which serves to drive the individual rotary bits in a manner that will hereafter be described.

The lower end of the bit blank 11 is recessed for receiving the driving mechanism for the

rotary bits. The recess, indicated generally at

17, is formed at its upper end with a plurality of cylindrical bores 18, 19 and 20 circumferentially spaced about a central bore 21. The driving pinion 16 on the lower end of the turbo-drill shaft 15

Application April 8, 1946, Serial No. 660,544

4 Claims. (Cl. 255—71)

1

This invention relates to a drill bit and more particularly to a drill bit for use in the drilling of oil wells and the like having a plurality of positively driven rotary cutters provided with abrasive grinding surfaces.

It has heretofore been the practice in oil drilling to use hard bits having a chipping or cutting action. Due to the fact that such bits are strong and can stand percussive forces, any cone of rock left uncut at the geometrical center of the hole being drilled will be crushed or broken free by the action of the drill bit. The crushed or broken portions of the rock are then forced out of the way by the circulating fluid.

In accordance with my present invention, however, rotary cutters which may be impregnated or surface-set with abrasive particles, such as diamonds, are used in place of the previous hard alloy cutter. With the use of such abrasive bits, a grinding action, rather than a cutting action, is produced. There is no percussive force possible in the case of diamond drill bits, nor is there sufficient clearance provided for cuttings to pass away from the face of the bit of greater size than are normally formed by the action of the diamonds in breaking down the granular structure of the rock.

Consequently, in the use of diamond bits, I have found it necessary to provide for a positive grinding action over the entire surface of the hole to be drilled, including the geometrical center of the hole. I accomplish this by providing a plurality of substantially cylindrical bits having lateral and lower grinding surfaces, with one of the bits of larger diameter than the others and with the bits so arranged that the peripheral marginal portion of the larger size bit overlies the geometrical center of the hole to be drilled. The bits are positively driven, independently of the rotation of the drill bit assembly as a whole, with the result that the linear speed of the peripheral marginal grinding portion of the larger size bit over the center of the hole gives an efficient grinding action at that point. The blind center that would otherwise exist in the case of previously used drill bits is thereby eliminated. By virtue of this arrangement, diamond bits of my invention may be used for drilling purposes where heretofore abrasive type bits have not proved satisfactory.

It is therefore an important object of this invention to provide a drill bit assembly having positively driven rotary bits provided with diamond or other abrasive particles, impregnated throughout or set upon the surfaces of the bits,

2

for exerting a grinding action in the drilling operation.

It is a further important object of this invention to provide a drill bit assembly in which the rotary cutters are so arranged as to eliminate the so-called "blind center" in the drilling operation.

It is a further important object of this invention to provide a drill bit assembly having a

plurality of substantially cylindrical, diamond or other abrasive impregnated or surfaced, bits, each positively driven and arranged substantially equidistant from the axis of the assembly, with one of the bits of sufficiently larger diameter to overlie the geometrical center of the hole to be drilled, whereby there is positive grinding action at that point due to the relatively high linear speed of the abrasive particles in passing therover.

Other and further important objects of this

invention will be apparent from the disclosures in the specification and the accompanying drawings.

Figure 1 is a bottom plan view of a drill bit assembly embodying the principles of my invention;

Figure 2 is a sectional view, with parts in elevation, taken substantially along the broken line

II-II of Figure 1; and

Figure 3 is a sectional view taken substantially along the line III-III of Figure 2.

The reference numeral 10 indicates generally a drill assembly embodying the principles of my invention. Said drill assembly comprises a bit blank 11 having an upper externally threaded

conical portion 12 for threading into a correspondingly internally threaded socket 13 of a holder 14, the latter being generally called a "sub."

The holder, or "sub," 14, is, in turn, threaded into the heavy drill collars attached to

the lower end of the string of drill pipes used in the drilling of oil wells and the like.

As shown, the drill assembly 10 is intended to be attached to the shaft 15 of a turbo-drill. Said shaft 15 extends freely through the holder 14

and the bit blank 11. The lower end of said shaft

15 carries a pinion 16 which serves to drive the individual rotary bits in a manner that will hereafter be described.

The lower end of the bit blank 11 is recessed for receiving the driving mechanism for the

rotary bits. The recess, indicated generally at

17, is formed at its upper end with a plurality of cylindrical bores 18, 19 and 20 circumferentially spaced about a central bore 21. The driving pinion 16 on the lower end of the turbo-drill shaft 15

extends into the central bore 21. Said pinion gear 16 is in driving relationship with driven pinion gears 22, 23 and 24 mounted, respectively, in the bores 18, 19 and 20. The pinion 24 is secured to a rotary cutter stub shaft 25 that is journaled at its lower end in a radial bearing 26 and at its upper end in a thrust bearing 26a. The pinion 23 is secured to a rotary bit stub shaft 27 mounted in radial and thrust bearings 28, and 28a. The arrangement for the other pinion 22 on its stub shaft 22a is similar to that illustrated and described. The radial bearings 26 and 28 are secured within enlarged bore portions 29 and 30, respectively, formed in the bit blank 11 as extensions of the bores 20 and 19, respectively.

The shaft 25 carries at its lower end a rotary bit 31 that is of larger diameter than the rotary bits 32 and 33 for a purpose that will later appear. Each of said rotary bits 31, 32 and 33 is of generally cylindrical shape with a substantially flat lower circular surface. Both the lateral cylindrical face and lower circular flat face of each of the rotary bits is impregnated or otherwise surfaced with abrasive particles, such as diamonds, indicated at 34. Each of the stub shafts is hollow and each of the drill bits is provided with an aligned circulation passage, as indicated by the reference numerals 35, 36 and 37 for the drill bits 31, 32 and 33, respectively. These circulation passages are for the purpose of permitting a circulating mud, pumped through the passages 50 and 51 in the drill pipe under high pressure, to pass into an equalizing chamber 52 and thence through the hollow stub shafts 22a, 25 and 27 and through the drill bits to emerge under the grinding surfaces of said bits and free said surfaces. The arrangement of circulation passages is merely illustrative and may be changed to suit the particular conditions under which the drilling is to be carried out.

The size and arrangement of the drill bits 31, 32 and 33 is such that the lateral cylindrical walls of said bits extend laterally outwardly from the lateral cylindrical wall of the bit blank 11, as indicated at 38, 39 and 40, respectively. This is for the purpose of preventing binding of the bit blank and holder in the drilling of a hole, or well. The bits 31, 32 and 33 cut a hole that is larger in diameter than the diameter of the bit blank 11 and holder 14.

In general, the axes of the rotary bits 31, 32 and 33, indicated by the reference characters *a*, *b* and *c*, respectively, are equi-distant from the true axis or center of the bit assembly, indicated by the reference character *A*. The center *A* is also the geometrical center of the hole to be drilled.

By virtue of this arrangement the larger diameter bit 31 has a peripheral marginal portion, indicated at *m*, that overlies the geometrical center *A*. It will also be noted that the peripheral marginal portion *m* must travel at substantially the maximum linear speed of any portion of the flat grinding surface of the bit 31, owing to the fact that said marginal portion *m* includes the periphery of the bit itself. This is a very important feature, since it is desirable in order to obtain efficient grinding action at the blind center *A* to have a relatively high linear speed of the abrasive particles 34 passing thereover.

In operation, the turbo-drill shaft 15 is rotated under relatively high speed to drive the individual drill bits 31, 32 and 33 through the intermeshing of the drive pinion 16 with the rotary bit pinions 24, 22 and 23, respectively. The rotary bits are

thus driven independently of the drive of the drill assembly 10 as a whole. Thus, the individual rotary bits may be driven in one direction, such as the clockwise direction indicated (Figure 2), while the bit assembly as a whole may be driven in the opposite direction.

It will be understood that although the drawings illustrate the drill bit assembly attached to the shaft of a turbo-drill, the assembly may also be used with the conventional turntable and kelly. The drill bit assembly of my invention has a number of advantages, among which may be mentioned ability of the drill to penetrate through hard rock at a rapid rate. Where the drill bit assembly is used in conjunction with a turbo-drill, which is capable of speeds ranging from 600 to approximately 1000 R. P. M., a particularly high rate of drilling can be realized without the use of any special system of gears to increase the cutter speed. By the provision of a separate drive for the rotary cutters, the cutters are not dependent upon friction from the wall of the hole to drive them, but are positively driven and therefore more positive in their grinding action. It is also possible by virtue of the construction of my drill bit assembly to insure proper circulation of the circulating mud. The spaces on the outside diameter between the three rotary bits give foreign bodies, such as rock fragments, rock bit teeth and the like that may be loose at the bottom of the hole, a chance to pass away without breaking up the diameters of the rotary bits themselves.

Instead of having the shafts of the several rotary cutters all parallel to each other, they can be at slight angular inclinations, and the lower grinding faces of the bits may thus be arranged in inclined planes to each other, either with the planes converging downwardly toward the center so as to give a convex appearance, or converging upwardly toward the center to give a concave appearance. It is preferred, however, that the lower grinding surfaces of the rotary bits be flat and lie all in the same plane. It will, of course, be understood that various details of construction may be varied through a wide range without departing from the principles of this invention, and it is, therefore, not the purpose to limit the patent granted hereon otherwise than necessitated by the scope of the appended claims.

What I claim is:

1. In a drill bit assembly, a plurality of rotary bits having circular lower generally plane grinding surfaces provided or surfaced with abrasive particles, one of said bits being of larger diameter than the other bits and having a peripheral marginal portion provided with such abrasive particles on its lower grinding surface overlying the geometric center of the hole to be drilled, and means for positively rotating said bits independently of the rotation of said assembly as a whole, whereby said peripheral marginal portion while rotating at a relatively higher linear speed than portions nearer to the center of said larger diameter bit is caused to exert an effective grinding action over said center during drilling.

2. In a drill bit assembly, a plurality of rotary bits having circular lower grinding surfaces all lying in substantially the same plane and provided or surfaced with abrasive particles, said bits being arranged with their axes substantially equally spaced about the axis of said drill assembly and one of said bits being of larger di-

ameter than the other bits and having a peripheral marginal portion provided with such abrasive particles on its lower grinding surface overlying the geometric center of the hole to be drilled, and means for positively rotating said bits independently of the rotation of said assembly as a whole, whereby said peripheral marginal portion while rotating at a relatively higher linear speed than portions nearer to the center of said larger diameter bit is caused to exert an effective grinding action over said center during drilling.

3. In a drill bit assembly, a plurality of rotary bits having circular substantially flat lower grinding surfaces provided with abrasive particles, said bits having stub shafts arranged with their axes equi-spaced about the axis of the drill assembly, said shafts and bits having bores therethrough providing passages for discharging a circulating fluid beneath said grinding surfaces and an axially extending driving shaft having driving connections with said stub shafts to positively rotate said bits independently of the rotation of said bits as a whole.

4. In a rotary driven drill bit assembly, a plurality of rotary bits having substantially flat, circular, lower grinding surfaces provided with abrasive particles, a separate shaft for each of said bits, a bearing for each shaft in which the

same is rotatable independently of the rotation of said assembly as a whole, said shafts being substantially equi-spaced about the axis of said drill assembly and one of said bits being of larger diameter than the other bits and having a peripheral marginal portion of its grinding surface overlying the geometric center of the hole to be drilled, whereby said peripheral marginal portion while rotating at a relatively higher linear speed than grinding surface portions nearer the center of said larger diameter bit is caused to exert an effective grinding action over said center during drilling.
